(57) **CLAIM**

The ornamental design for a beauty apparatus, as shown and described.

DESCRIPTION

FIG. 1 is a top, front, right perspective view of a beauty apparatus showing my new design;
FIG. 2 is a bottom, rear, left perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a bottom, rear, left perspective view of the detail “9” identified in FIG. 2, shown enlarged for clarity of disclosure; and,
FIG. 10 is a front elevation view of the detail “10” identified in FIG. 3, shown enlarged for clarity of disclosure.
In the drawings, the equal-length broken lines depict portions of the beauty apparatus and form no part of the claimed design.

1 Claim, 10 Drawing Sheets
